UNITED STATES PATENT OFFICE.

CHARLES H. BONNETT, OF PORT HURON, MICHIGAN.

TUNNELING AND EXCAVATING MACHINE.

1,093,603.

Specification of Letters Patent. Patented Apr. 21, 1914.

Application filed October 22, 1913. Serial No. 796,554.

To all whom it may concern:

Be it known that I, CHARLES H. BONNETT, a citizen of the United States of America, residing at Port Huron, in the county of St. 5 Clair and State of Michigan, have invented certain new and useful Improvements in Tunneling and Excavating Machines, of which the following is a specification, reference being had therein to the accompanying 10 drawings.

This invention relates to a tunneling and excavating machine especially designed for digging tunnels, sewers, conduits and other subterranean passage.

15 The primary object of my invention is to provide a novel machine that can be expeditiously advanced for economically excavating and removing dirt from the point of operation.

20 A further object of this invention is to provide a machine of the above type embodying a novel rotary cutter that can be easily and quickly adjusted for removing desired quantities of earth.

25 The invention in its broadest aspect involves positive and reliable means, as hereinafter set forth, for advancing and maintaining a rotary cutter in engagement with the earth, the cutter having a radial adjust-

30 ment whereby an opening of a desired diameter can be worked. To this end, I have devised a machine embodying a plurality of structural elements which when combined, provide a durable, easily adjusted and 35 quickly operated machine for producing subterranean passages that can be used for various purposes.

The principal elements of the invention— 40 namely, a main frame and braces, a feed screw and one of its bearing supports, a rotary adjustable cutter, a conveyer, together with the operating mechanism for said conveyer and the rotary cutter, will be herein-after separately and specifically described in 45 detail, together with the novel arrangement and objects accomplished by such a combination of elements.

The preferred embodiments of the invention are illustrated in the accompanying 50 drawings but it must be understood that the same are susceptible to such changes, as in the size, shape and manner of assemblage,

without departing from the scope of the appended claims.

In the drawings, Figure 1 is a side elevation of the machine, partly broken away and partly in section; Fig. 2 is an enlarged plan of a portion of the rotary cutter; Fig. 3 is a side elevation of the same; Fig. 4 is a horizontal sectional view of a portion of the 55 machine; Fig. 5 is a cross sectional view taken on the line X—X of Fig. 1, looking in the direction of the arrows of said figures. Fig. 6 is a side elevation of a machine illustrating a modification of the invention, and 60 Fig. 7 is an end view of the same.

The greater part of my machine is constructed of strong and durable structural steel and consists of parts that are easily assembled to provide a rigid perfectly balanced machine for rapidly excavating with the requisite degree of safety to the workmen or attendants of the machine.

Considering now the principal elements of the invention, reference will be had to the 75 main frame and braces.

The main frame comprises a sill or foundation 1 provided with uprights 2 and 3. Suitably mounted in the upper ends of the uprights 2 and 3 are hand operated jacks 4 80 adapted to engage a roof timber 5 and securely anchor the uprights 2 and 3 between the floor and roof of a subterranean entry or working 6. The sides of the uprights 2 and 3 have socket 7 or connections for angularly disposed braces 8, which have the upper ends thereof provided with jacks 9 retaining timbers 10 against the roof of the 85 entry 6.

Adjacent to the upright 2 is an additional 90 upright 11 coöperating with the uprights 2 and 3 in supporting a horizontal platform 12. This platform supports the operative mechanism for the rotary cutter and conveyer of the machine, and said mechanism 95 will be hereinafter considered in detail.

The feed screw and one of its bearing supports.—at the forward end of the machine is arranged a semi-circular channel frame 13 and connecting diametrically, opposed 100 sides of said frame, adjacent to the ends thereof, is a transverse support 14, preferably made of an inverted channel bar. The support 14 intermediate the ends thereof has

a bearing 15 longitudinally alining with bearings 16 and 17 carried by the uprights 2 and 3 respectively. Journaled in these bearings is a feed screw 18 having the forward end thereof provided with a longitudinal groove adapted to receive a spline or key, and the rear end of said screw has threads 19 for a nut 20, said nut being rotated through the medium of radially disposed handles 21.

Arranged upon the forward end of the feed screw 18 and engaging the rear sides of the bearing 15 is a spacer sleeve 22 that positions a large gear wheel 23 upon the feed screw relatively to the channel frame 13 and the platform 12. The larger gear wheel 23 has a spline or key engaging in the groove of the feed screw whereby said gear wheel and said feed screw will revolve in unison and permit of the feed screw being adjusted longitudinally of the large gear wheel.

The semi-circular channel frame 13 and the support 14 constitute a bearing support that co-operates with the main frame and its braces in providing a rigid structure for supporting the driven elements of the machine.

The rotary adjustable cutter.—Mounted upon the forward end of the feed screw 18 is a cross head 25 and adjustably mounted upon said cross head is a bitholder 26 having an opening 27 to receive the end of said cross head. The bit-holder 26 has a transverse opening 28 to receive the shank 29 of a bit or cutter 30. The bit or cutter is channel shaped and engages a side wall of the holder 26, whereby it is braced during its cutting action. The shank 29 of the bit is retained within the opening 28 by a set screw 31 or other fastening means.

The bit holder 26 is provided with apertured lugs 32 and pivotally mounted between said lugs by a transverse pin 33 is the outer end of a rack bar 34. The inner end of the rack bar 34 extends through a housing 35 riveted or otherwise secured to the cross head 25, and journaled in said housing is a guide roller 36 and a pinion 37, the shaft of said pinion having a crank 38 whereby the pinion can be revolved to move the rack bar 34 in a desired direction through the housing 35 and thereby shift the bit holder 26 longitudinally of the cross head 25.

The conveyer.—Extending rearwardly from the uprights 3 are brackets 39 supporting a driven shaft 40. The shaft 40 has a roll 41 and trained over this roll is an endless apron or conveyer 42 that is also trained over rolls 43 and 44. The former is revolvably supported at the base of the bearing frame 13 and the latter is revolvably supported by the uprights 3. The apron 42 is adapted to receive material cut by the bit

30 and conveys the material to the rear end 65 of the machine from where it can be conveniently removed.

The operative mechanism for the conveyer and the rotary cutter.—Located upon the platform 12 is an internal combustion engine 45 or other source of power for revolving a shaft 46, journaled in bearings 47, carried by the platform 12. One end of the shaft 46 has a small gear wheel 48 meshing with the large gear wheel 23. The opposite end of the shaft 46 has a bevel gear wheel 49 meshing with a similar wheel 50 mounted upon the shaft 51, journaled in a bearing 52 carried by the platform 12. The shaft 51 has a belt wheel for a belt 53 that extends 80 downwardly under a belt wheel 54 mounted upon an end of the shaft 40 of the conveyer.

Arranged upon the shaft 46 are clutches 55 and 56, the former controlling the operation of the conveyer 42 and the latter controlling the operating of the feed screw 18. The clutches 55 and 56 are of the ordinary and well known type common to various types of machines.

Before considering the modification shown in Figs. 6 and 7 it is thought best to consider the operation of the preferred machine illustrated in Figs. 1 to 5 inclusive.

Operating under ordinary conditions only a few workmen are required to manipulate the machine and advance the same as the work progresses in the working 6. Before starting the machine, the bit holder 26 is placed centrally of the machine, that is, at a point intermediate the ends of the cross head 25. The end wall of the working 6 is preferably provided with a small recess to receive the bit 30 and then the machine can be placed in operation by starting the engine 45 and throwing in the clutches 55 and 56. After the rotary cutter has made one complete revolution, the rack bar 34 can be adjusted to shift the bit holder 26 outwardly upon the cross head 25, whereby the bit 30 thereof, during the next revolution of the rotary cutter will remove material and thereby increase the diameter of the original recess. By repeatedly adjusting the rack bar 34, the original end walls of the working 6 is removed and during this time the material has been conveyed to the rear end of the machine by the apron 42.

After the described diameter of the working 6 has been reached, the bit holder is returned to its normal position centrally of the machine. The nut 20 is then rotated to advance the feed screw 18, whereby the bit of the rotary cutter will obtain a fresh hold upon the end wall of the working 6 and proceed in the manner just described to remove said end wall. After the feed screw 18 has been advanced as far as possible it is re-

stored to its normal position and the machine bodily moved forward and anchored in the working, whereby additional operations can be carried on.

5 Reference will now be had to Figs. 6 and 7 of the drawings, illustrating a modified form of machine. The working 6 is provided with a temporary road bed 57 for the rails 58 of a track. Movable upon the rails 10 58 of the track are trucks 59 supporting a rectangular frame work 60. The forward end of the frame work 60 has a bracket 61 provided with a bearing 62 alining with bearings 63 carried by the frame work.

15 The bearings 62 and 63 support a revoluble feed screw 64 similar in all respects to the feed screw 18 of the preferred form of construction. The feed screw 64, besides having the adjusting nut 65, has a large gear 20 wheel 66 meshing with a small gear wheel 67 mounted upon the armature shaft of an electric motor 68, carried by the frame work 60. The motor 68 is of the conventional form and can be driven from a suitable 25 source of electrical energy located interiorly or exteriorly of the working 6.

The forward end of the feed screw 64 has a cross head 69 and adjustably mounted upon said cross head are pluralities of bit holders 30 70 having bits 71. The bit holders 70 are equally spaced upon the cross head 69 whereby the bits 71 thereon will tend to produce concentric angular kerfs or grooves, the formation of which crumbles and disintegrates the end walls of the working 6, whereby the feed screw 64 can be continuously or intermittently advanced.

During the operation of the machine the trucks 59 are blocked or anchored relatively 40 to the track and the sides of the frame work 60 are braced relatively to the walls of the working by angularly disposed braces 72 constructed similar to the braces 8 of the preferred form of machine.

45 As fast as the excavating is accomplished, the walls of the working are lined, as at 73, said lining providing a smooth and uninterrupted conduit that can be used for various purposes.

50 What I claim is:—

1. In a tunneling and excavating machine, a main frame, a revoluble feed screw carried thereby, a rotary adjustable cutter carried by said feed screw, a semi-circular bearing support for said cutter and means carried by said main frame work for revolving said feed screw and the cutter thereof.

2. In a tunneling and excavating machine, a main frame, a revoluble feed screw carried thereby, a rotary adjustable cutter carried by said feed screw, a semi-circular bearing support for said cutter means carried by said main frame work for revolving said feed screw and the cutter thereof, and means

carried by said feed screw for adjusting the same relatively to said main frame.

3. An excavating machine comprising a bearing frame, a feed screw carried thereby, a cross head carried by said feed screw, a bit holder adjustably mounted upon said cross head, means carried by said cross head for manually adjusting said bit holder, and means in proximity to said frame for imparting movement to said feed screw.

4. An excavating machine comprising a movable frame, a revoluble driven feed screw supported thereby, a cross head carried by said feed screw, bit holders adjustable upon said cross head, means carried by said cross head for manually adjusting said bit holder, means supported by said frame for revolving said feed screw, and means carried by said feed screw for adjusting the same relatively to said frame.

5. In a tunneling and excavating machine, a main frame, a bearing support, a feed screw revolubly supported by said frame and said support, a rotary cutter supported by said feed screw and adapted to be manually adjusted radially thereto, and means carried by said main frame for imparting movement to said feed screw.

6. In a tunneling and excavating machine, a portable frame, a feed screw adjustably and revolubly supported thereby, a cross head carried by said feed screw, a bit holder supported by said cross head and adapted to be manually adjusted relatively to said feed screw, means carried by said frame and adapted to operate said cutter.

7. In an excavating machine, a rotary cutter, said cutter comprising a cross head, a bit holder slidable thereon, and means including a rack and pinion adapted to be manually operated for shifting said bit holder longitudinally of said cross head.

8. In a tunneling and excavating machine, a main frame, a rotary cutter at the forward end thereof, comprising a cross head, a bit holder slidable upon said cross head, manually operated means for shifting said bit holder longitudinally of said cross head, means carried by said frame adapted to rotate said cutter, and means at said frame for longitudinally adjusting said rotary cutter relatively to said frame.

9. In a tunneling and excavating machine, a bearing frame, a semi-circular bearing support, a feed screw revolubly and adjustably supported by said frame and support, a cross head carried by said feed screw, a bit holder slidable upon said cross head, means including a rack and pinion for shifting said bit holder longitudinally of said cross head, and means adapted to operate said feed screw.

10. In a tunneling machine, a main frame, a bearing support independent of said

frame, a driven feed screw arranged longitudinally of said frame and said support and adapted to be adjusted longitudinally thereof, a cross head carried by said feed screw, and bit holders arranged upon said cross head and adapted to be manually adjusted.

In testimony whereof I affix my signature in presence of two witnesses.

CHARLES H. BONNETT.
